United States Patent Office

Des. 180,956
Patented Sept. 10, 1957

180,956

COMBINED MAGNIFIER AND BOOKMARK

Kenneth D. Maier, Mendon, N. Y., assignor to Bausch & Lomb Optical Company, Rochester, N. Y., a corporation of New York

Application October 8, 1956, Serial No. 43,268

Term of patent 14 years

(Cl. D57—1)

FIG. 1

FIG. 3

Fig. 1 is a front elevational view of a combined magnifier and bookmark, showing my new design.

Fig. 2 is a side view thereof.

Fig. 3 is a sectional view taken on line 3—3 of Fig. 1.

The rear of the design not shown in the same as the front shown.

I claim:

The ornamental design for a combined magnifier and bookmark, substantially as shown and described.
